UNITED STATES PATENT OFFICE

153,798

DESIGN FOR A FISHING LINE SINKER OR THE LIKE

Clair L. Hinkson, Seattle, Wash., assignor to
Hinkson Mfg. Co., Seattle, Wash., a partnership

Application October 10, 1947, Serial No. 141,843

Term of patent 14 years

(Cl. D31—4)

To all whom it may concern:

Be it known that I, Clair L. Hinkson, a citizen of the United States of America, residing at Seattle, in the county of King, and State of Washington, have invented a new, original, and ornamental Design for a Fishing Line Sinker or the like, of which the following is a specification, reference being had to the accompanying drawing, forming part thereof.

Figure 1 is a side elevational view of a fishing line sinker or the like, showing my new design.

Figure 2 is a front perspective view thereof.

Figure 3 is a bottom plan view thereof.

Figure 4 is a front top perspective view thereof.

Figure 5 is a bottom rear perspective view thereof.

I claim:

The ornamental design for a fishing line sinker or the like, as shown.

CLAIR L. HINKSON.
